UNITED STATES PATENT OFFICE.

FREDERICK E. ASHMUN, OF PROVIDENCE, RHODE ISLAND.

DESIGN FOR A RING.

Application filed November 23, 1922. Serial No. 4,364. Term of patent 3½ years.

To all whom it may concern:

Be it known that I, FREDERICK E. ASHMUN, a citizen of the United States, residing at Providence, in the county of Providence and State of Rhode Island, have invented a new, original, and ornamental Design for Rings, of which the following is a specification, reference being had to the accompanying drawing, forming part thereof.

The figure is a perspective view of a ring, showing my new design.

I claim:

The ornamental design for a ring, as shown.

FRED. E. ASHMUN.
